(No Model.)

C. CATHAN.
THILL COUPLING.

No. 557,552.

Patented Apr. 7, 1896.

UNITED STATES PATENT OFFICE.

CHARLES CATHAN, OF BELOIT, KANSAS.

THILL-COUPING.

SPECIFICATION forming part of Letters Patent No. 557,552, dated April 7, 1896.

Application filed June 8, 1895. Serial No. 552,151. (No model.)

To all whom it may concern:

Be it known that I, CHARLES CATHAN, a citizen of the United States, residing at Beloit, in the county of Mitchell and State of Kansas, have invented a new and useful Thill-Coupling, of which the following is a specification.

This invention relates to an improvement in thill-couplings.

10 The object of the present invention is to simplify and improve the construction of devices of the nature above referred to, and to provide a novel form of coupling by means of which the pole or shafts may be attached 15 to the axle of any vehicle that is provided with the usual axle-clip without removing the coupling-pin.

Other objects and advantages of the invention will appear in the course of the subjoined 20 description.

To the above end the invention consists in certain novel features and details of construction and arrangement, as hereinafter fully described, illustrated in the drawings, and 25 finally embodied in the claims.

In the accompanying drawings, Figure 1 is a perspective view of the thill-iron constructed in accordance with this invention and having the locking-plate secured thereto. Fig. 2 30 is a detail perspective view of the sliding locking-plate detached. Fig. 3 is a similar view of the bearing-block and the yoke by means of which said block is connected with the coupling-pin of the axle-clip. Fig. 4 is a 35 longitudinal section through the axle-clip and thill-iron, showing the several parts in operative relation.

Similar numerals of reference designate corresponding parts in the several figures of the 40 drawings.

Referring to the accompanying drawings, 1 designates an axle-clip of the usual construction formed with an oppositely-disposed pair of forwardly-projecting rigid arms 2, said 45 arms being provided with horizontally-alined perforations for the reception of the coupling pin or bolt 4 and spaced a sufficient distance apart to receive between them the rear end of the thill-iron, all being of the ordinary construction, such as is used in connection with the forward axles of the great majority of buggies, carriages, and other vehicles.

5 designates a bearing-block of suitable

material which is grooved in one of its faces corresponding to and adapted to fit snugly 55 against the coupling pin or bolt 4. Said bearing-block is supported with relation to said coupling pin or bolt by means of a thin metallic yoke 6, comprising an oppositely-disposed pair of arms, which are perforated to 60 admit the coupling pin or bolt 4, and a cross-bar or web 7, connecting said arms and embracing the opposite side of the bearing-block 5 to that upon which the groove is formed. The thickness of said bearing-block about 65 corresponds to the diameter of the coupling pin or bolt 4.

The thill-iron (indicated at 8) is provided in its rear end with a vertically-extending slot 9, which is open at the bottom to admit of 70 said thill-iron being placed over and brought into engagement with the coupling pin or bolt of the axle-clip. The rear wall or portion of the thill-iron is extended downwardly a sufficient distance below the plane of the lower 75 face of said thill-iron to admit of the same being perforated, as shown at 10, said perforation being adapted to receive a rearwardly-projecting pin or stud 11 on a slotted locking-plate 12. The locking-plate 12 is provided 80 with a longitudinally-extended slot 13 and is secured to the lower face of the thill-iron by means of a headed screw or rivet 14, which passes through and engages said slot 13 and enters a socket or perforation in the thill-iron. By means of this construction the locking-plate 12 is adapted to slide longitudinally 85 of the thill-iron a sufficient distance to withdraw the pin or stud 11 from the perforation 10, above referred to. 90

15 indicates a lug or projection on the forward end of the sliding locking-plate, for the purpose of enabling said locking-plate to be rocked upon the pin or screw 14, and engaging the pin 11 with the perforation 10, or disengaging the same, as required. 95

16 represents a thumb-screw which passes through a threaded perforation in the rear end of the locking-plate adjacent to its interlocking connection with the rear portion of 100 the thill-iron and in vertical alinement with the open slot 9 of the thill-iron, said screw being adapted also to engage a socket in the lower face of the bearing-block 5, yoked to the coupling pin or bolt 4 of the axle-clip. 105

16^a is a lock-nut for the screw 16.

From the foregoing description the operation of the thill-coupling will be readily understood.

With the bearing-block pendent beneath the coupling pin or bolt of the axle-clip the slotted rear end of the thill-iron is passed over said coupling pin or bolt until the latter rests within the upper end of the open slot of the thill-iron. The locking-plate is now manipulated until the rearwardly-projecting pin or stud 11 thereof is brought into line with the perforation 10 in the rear wall or portion of the thill-iron. The sliding locking-plate is then moved rearwardly until said pin 11 passes through the perforation 10 and the rear end of said locking-plate abuts against the corresponding portion of the thill-iron. The thumb-screw 16 is now operated to force the bearing-block snugly against the coupling pin or bolt of the axle-clip, at the same time drawing the thill-iron firmly and snugly down upon said coupling pin or bolt. The parts are thus firmly pressed together and all loose play and rattling are effectually prevented. By means of the set-screw 16 wear is taken up as fast as it occurs.

The device is so simple and easy of manipulation that the change from a pole to shafts may be very quickly and easily effected, and this without the aid of tools.

Should the wearing-block 5 become too much worn, it will be evident that it may be quickly and easily replaced by a new one.

If desired, the yoke for the block 5 may be dispensed with and said block placed in position by hand.

Changes in the form, proportion, and minor details of construction may be resorted to

without departing from the spirit or sacrificing any of the advantages of this invention. 40

Having thus described the invention, what is claimed as new, and desired to be secured by Letters Patent, is—

1. In a thill-coupling, the combination with the axle-clip carrying the coupling pin or bolt; 45 of a thill-iron provided with a downwardly-opening slot receiving said coupling pin or bolt, a bearing-block fitting in said slot and bearing against the under side of the pin or bolt, and a locking-plate having a pivotal connection with the under side of the thill-iron at one side of the slot therein and a positive interlocking engagement with the iron at the other side of said slot, and a set-screw mounted in the locking-plate adjacent to the interlocking connection thereof with the thill-iron and adapted to work against the under side of said bearing-block, substantially as described. 55

2. In a thill-coupling, a thill-iron provided with a downwardly-opening slot, and a locking device adapted to close the mouth of said slot, in combination with a bearing-block, a yoke for supporting said bearing-block with relation to the coupling-pin of an axle-clip, and a thumb-screw carried by said locking device and adapted to be engaged with said bearing-block, for the purpose and substantially as described. 65

In testimony that I claim the foregoing as my own I have hereto affixed my signature in 70 the presence of two witnesses.

CHARLES CATHAN.
